Primary Examiner — Susan Bennett Hattan*Assistant Examiner* — Lauren D McVey*(74) Attorney, Agent, or Firm* — W&K IP(57) **CLAIM**

The ornamental design for mounting arm for display stand, as shown and described.

DESCRIPTION

FIG. 1 is a perspective view of a mounting arm for display stand showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a position of use perspective view showing our new design with environment.

The broken lines that are immediately adjacent to the shaded areas and define unshaded regions depict the bounds of the

(Continued)

claimed design. All other broken lines are directed to environment. The broken lines form no part of the claimed design.
